(57) **CLAIM**

We claim the ornamental design for an amplifier with digital
video disc player, as shown and described.

DESCRIPTION

FIG. 1 is a top perspective view of a first embodiment of an
amplifier with digital video disc player of the present
invention;

FIG. 2 is a front view thereof;

FIG. 3 is a rear view thereof;

FIG. 4 is a top view thereof;

FIG. 5 is a bottom view thereof;

FIG. 6 is a first side view thereof;

FIG. 7 is a second side view thereof;

FIG. 8 is a top perspective view of a second embodiment of
an amplifier with digital video disc player of the present
invention;

FIG. 9 is a front view thereof;

FIG. 10 is a rear view thereof;

FIG. 11 is a top view thereof;

FIG. 12 is a bottom view thereof;

FIG. 13 is a first side view thereof; and,

FIG. 14 is a second side view thereof.
